UNITED STATES PATENT OFFICE.

JEREMIAH C. FITZGERALD, OF KILBOURN, WISCONSIN.

SHAFT-HANGER.

1,387,044.

Specification of Letters Patent. Patented Aug. 9, 1921.

Application filed July 21, 1920. Serial No. 397,998.

To all whom it may concern:

Be it known that I, JEREMIAH C. FITZGERALD, a citizen of the United States, and a resident of Kilbourn, in the county of 5 Columbia and State of Wisconsin, have invented certain new and useful Improvements in Shaft-Hangers, of which the following is a specification.

This invention relates to improvements in 10 a hanger for shafts, such as are used in connection with machines of various kinds for transmitting power thereto, and it consists in certain peculiarities of the construction and the combination of parts hereinafter 15 fully described and specifically claimed.

The invention has for its principal object 20 the production of a shaft hanger having the qualities of all adaptability that is requisite in view of the various positions, drops and sizes of shafts for which it may be used, of convenience in mounting and dismounting the shaft and of possibility of cheap manufacture.

Another object is to provide a shaft 25 hanger having a flexible bearing member for the shaft whereby undue wear and excessive heating will be prevented.

Still another object is to so construct and 30 arrange the parts of the device that the bearing members for the shaft can be readily changed to accommodate shafts of different sizes.

Other objects and advantages of the invention will be set forth in the following 35 description and explanation.

In the accompanying drawing which serves to illustrate an embodiment of the invention—

Figure 1 is a side view of a shaft hanger 40 showing it mounted in one of the positions for which it is adaptable.

Fig. 2 is a vertical sectional view taken on line 2—2 of Fig. 1 looking in the direction indicated by the arrows.

Fig. 3 is a detached plan view of the supporting base.

Fig. 4 is a plan sectional view taken on line 4—4 of Fig. 1.

Fig. 5 is a slightly enlarged detached perspective view of the lower portion of the frame of the hanger showing the bearing for the shaft in the act of being removed from said frame, and

Fig. 6 is an end view of a modified form 55 of the keeper or retainer for the bearing sleeve or member for the shaft showing said

sleeve or member in position within said keeper.

Corresponding numerals of reference designate like parts throughout the different 60 views of the drawings.

In the drawings, I have shown the hanger as being mounted on an overhead support and as depending therefrom, and in the following description and explanation will so 65 refer to the parts or elements, but I desire it to be understood that the device can be mounted to depend from a ceiling or elevated support, or to extend upwardly from a floor or support, or if desired, can be 70 mounted on a vertical wall or support so as to extend laterally or horizontally therefrom, and in any of said positions properly maintain a shaft.

Referring now to Figs. 1 and 2 of the 75 drawing, the reference numeral 10 designates a portion of a ceiling or elevated support to which is horizontally secured by means of bolts 11 a supporting base which is designated as a whole by the reference numeral 80 12 and consists of an elongated plate or bar, by preference, substantially U-shaped in cross-section. This supporting base is provided at each of its ends with a foot 13 disposed in the same plane and each of said 85 feet is provided with an opening 14 for the reception of the bolts 11 used in securing it to the permanent or fixed support 10 of a building or structure. As shown, the base 12 is deflected between the feet 13 thereof 90 and said deflected portion is provided with a pair of spaced longitudinally disposed slots 15 for the reception of screw-bolts 16 one of which is located in each of said slots. As shown in Figs. 1 and 2 of the drawings, each 95 of the bolts 16 is of the bent or hooked type and is extended laterally at one of its ends through an opening 17 located near the free end of one of the prongs 18 of the frame of the hanger which frame is designated as a 100 whole by the reference numeral 19 and is formed into a substantially U-shaped member as shown.

By preference, the frame 19 is made of material substantially U-shaped in cross-section and so that when bent to form the forked or substantially U-shaped frame, the channels of the prongs 18 will be presented outwardly or opposite each other as will be clearly understood by reference to Figs. 110 4 and 5 of the drawing, in which views it will be observed that the adjacent surfaces

of the prongs 18 of the frame 19 are slightly rounded. That end of each of the screw-bolts 16 adjacent the openings 17 of the arms 18 in which they are located is provided with a head 20 to securely hold said bolts in position. Threaded on each of the bolts 16 above the base 12 is a nut 21 which preferably rest on washers 22 interposed between said nuts and the base. By this arrangement it is apparent that the prongs 18 of the frame 19 of the hanger can be adjusted longitudinally with respect to the base or at right angles thereto. Each of the arms 18 of the hanger frame is provided on its inner surface with a series of openings 22 located one above the other and by preference longitudinally elongated as shown. The openings 23 of one of the arms 14 are located directly opposite the openings in the other arm 18 of the hanger frame and are for the reception and retention of the supporting member 24, which by preference has its ends substantially rectangular in shape like the shape of the openings 23 in which said ends are adapted to fit. This arrangement of the ends of the supporting member or bar 24 and said openings will prevent undue rocking movement of said bar or member. The member 24 is provided at its middle with a transversely disposed opening 25 for the reception and engagement with a screw-bolt 26 which has one of its ends formed with an eye or loop 27 for the purpose to be presently explained. The screw-bolt 26 is adjustably mounted in the opening 25 of the bar or member 24 and may be held in the desired adjusted position by means of nuts 28 engaging said bolt above and below said member.

Transversely located in the eye 27 of the bolt 26 is a bolt 29 which has a head 30 on one of its ends and engages a nut 31 with its other end. This bolt 29 is extended through suitable openings in the ears or extensions 32 on the members 33 and 34 of the keeper or retainer for the bearing sleeve, for the shaft. One of these ears or extensions 32 is located as shown in Fig. 1 on each side of the eye 27 and said extensions are held in such positions by means of the bolt 29, its head 30 and nut 31 as is obvious.

The members 33 and 34 which constitute the keeper or holder for the bearing sleeve for the shaft are substantially semi-circular in shape and one of said members, for instance, the member 33, has on its end opposite its extension 32, a hook 35 which engages another hook 36 on the adjacent end of the member 34, thus detachably locking the members 33 and 34 together, yet in such a manner that when the screw-bolt 29 is loosened or removed from the extensions 32 the members 33 and 34 can be separated. Each of these members is by preference bellied outwardly as is clearly shown in Fig.

4 of the drawing, so that their edges will bite into or securely engage the sleeve 37 which is by preference split as indicated in Figs. 1 and 6 of the drawings and made of wood or other slightly flexible material in order to prevent undue wear and excessive heating when the shaft is operated therein and so that said sleeve may be adapted to shafts of different sizes. Any suitable material may be placed in the space 38 between the adjacent edges of the sleeve 37 at its split portion, so as to slightly expand the sleeve 37 or allow it to be contracted by the pressure of the members 33 and 34 of the keeper as may be required by the size of the shaft located in the cavity or opening of said sleeve.

In Fig. 6 of the drawing I have shown a modification in the construction of the keeper or retainer for the sleeve 37 which I may sometimes employ and which consists of a split circular band-like member 39 which has at its split portion apertured extensions 32 for the same purpose as the extensions 32 on the members 33 and 34 above described. In this modification, the band-like member 39 is also outwardly beveled as are the parts 33 and 34 shown in Fig. 4 of the drawing and above mentioned. This outwardly bellied construction of the bearing sleeve keeper not only performs the function of securely holding the sleeve 37 or biting into the same, but it also serves the purpose when the bearing sleeve 37 is located in the positions shown in Figs. 1, 2 and 4 of the drawings, to contact with the inner rounded surfaces of the prongs 18 of the frame, in such a manner as to assist in holding the sleeve 37 in proper position between said prongs, yet, when it is desired to detach or remove the support 24 and its members from the frame for any purpose, the above named construction will permit the keeper and the sleeve to be readily moved from between the prongs to one side thereof, when the keeper may be turned on the pivot bolt 29 until it assumes about the position shown by continuous lines in Fig. 5, and by dotted lines in Fig. 2 of the drawing, when it is obvious that the supporting bar 24 may be moved lengthwise thereof into one of the openings 23 of the prongs of the frame which will disengage the other end of said supporting bar from the opposite opening in the opposite prong of the frame and permit the supporting bar and its attachments to be removed from the frame for the purpose of changing sleeves to accommodate shafts of different sizes.

Having thus fully described my invention, what I claim as new and desire to secure by Letters Patent is—

1. A shaft hanger consisting of a supporting base adapted to be fastened to a permanent support, a U-shaped frame secured at

its ends to said base and having in its inner walls opposed and longitudinally spaced openings, a transversely disposed supporting member detachably located in a pair of said

5 openings, a rod threaded in said supporting member between the ends thereof, a shaft bearing mounted on one end of said rod and adapted so that before attaching the shaft said bearing may be moved outwardly for 10 the purpose of permitting the detachment and replacement of the supporting member in any of the openings of the frame.

2. In a shaft hanger, the combination with a suitably supported base, of a substantially 15 U-shaped frame secured at its ends to said base, a transversely disposed supporting member mounted on the frame, a keeper consisting of a band having external projections directed toward said supporting

20 member, a bearing member located within said keeper, a connection uniting said projections to said supporting member, said keeper and bearing member being held against vertical movement by the inner walls 25 of the frame and against horizontal movement by the said supporting member.

3. In a shaft hanger, the combination with a suitably supported base, of a substantially U-shaped frame secured at its ends to said 30 base, a transversely disposed supporting member mounted in the frame, a keeper consisting of a broken band having its ends converging and directed toward said supporting member, a bearing member located 35 within said keeper, a connection uniting the free ends of the band to said supporting

member, said keeper and bearing member being held against vertical movement by the inner walls of the frame and against horizontal movement by the said supporting 40 member.

4. In a shaft hanger, the combination with a supporting base having a deflected portion provided with longitudinally extended slots, of a substantially U-shaped frame mounted 45 at its ends for adjustment longitudinally with respect to the base and having in its inner walls a series of longitudinally disposed and spaced openings, of a transversely disposed supporting member detachably located at its ends in a pair of said openings, an expandible keeper pivotally connected to said member, and a flexible split bearing member for a shaft located within said keeper. 50

5. In a shaft hanger, the combination with a supporting base, of a substantially U-shaped frame mounted at its ends on said base and having in its inner walls a series of longitudinally disposed and spaced openings, of a transversely disposed supporting member detachably located at its ends in a pair of said openings, an expandible keeper pivotally connected to said member, said keeper being cross-sectionally outwardly bel- 60 lied, and a flexible split bearing member for a shaft located within said keeper. 65

In testimony whereof, I have hereunto set my hand, at Kilbourn, Wisconsin, on this, the 17th day of July, 1920.

JEREMIAH C. FITZGERALD.
